CLAIM

The ornamental design for a dashboard panel, as shown.

DESCRIPTION

FIG. 1 is a front perspective view of a dashboard panel showing my new design.

FIG. 2 is a front view in elevation thereof.

FIG. 3 is one side view in elevation thereof.

FIG. 4 is a bottom plan view thereof.

FIG. 5 is a rear view in elevation thereof in inverted condition.

FIG. 6 is a side view in elevation thereof in inverted condition opposite to that shown in FIG. 3, and

FIG. 7 is a top plan view thereof.
